United States Patent Office

Des. 208,453
Patented Sept. 5, 1967

208,453

DESK PLAQUE

Herbert P. Van Ostrand, Studio City, Calif., assignor to Vomar Products, Inc., Burbank, Calif., a corporation of California

Filed Sept. 1, 1966, Ser. No. 3,686

Term of patent 14 years

(Cl. D1—12)

I claim:

The ornamental design for a desk plaque, as shown.
